(57) **CLAIM**

The ornamental design for a seating, as shown and described.

DESCRIPTION

FIG. 1 is an isometric view of a seating showing a first embodiment of my new design.

FIG. 2 is a left side elevational view of the seating of FIG. 1, the right side elevational, front elevational, and back elevational views being identical thereto.

FIG. 3 is a top plan view of the seating of FIG. 1.

FIG. 4 is a bottom plan view of the seating of FIG. 1.

FIG. 5 is a side elevational view rotated approximately 45 degrees from the side elevational view of FIG. 2.

FIG. 6 is an isometric view of a seating showing a second embodiment of my new design.

FIG. 7 is a left side elevational view of the seating of FIG. 6, the right side elevational, front elevational, and back elevational views being identical thereto.

FIG. 8 is a top plan view of the seating of FIG. 6.

FIG. 9 is a bottom plan view of the seating of FIG. 6.

FIG. 10 is a side elevational view rotated approximately 45 degrees from the side elevational view of FIG. 7.

FIG. 11 is an isometric view of a seating showing a third embodiment of my new design.

FIG. 12 is a left side elevational view of the seating of FIG. 11, the right side elevational, front elevational, and back elevational views being identical thereto.

FIG. 13 is a top plan view of the seating of FIG. 11.

FIG. 14 is a bottom plan view of the seating of FIG. 11.

FIG. 15 is a side elevational view rotated approximately 45 degrees from the side elevational view of FIG. 12.

FIG. 16 is an isometric view of a seating showing a fourth embodiment of my new design.

FIG. 17 is a left side elevational view of the seating of FIG. 16, the right side elevational, front elevational, and back elevational views being identical thereto.

FIG. 18 is a top plan view of the seating of FIG. 16.

FIG. 19 is a bottom plan view of the seating of FIG. 16.

FIG. 20 is a side elevational view rotated approximately 45 degrees from the side elevational view of FIG. 17.

FIG. 21 is an isometric view of a seating showing a fifth embodiment of my new design.

FIG. 22 is a left side elevational view of the seating of FIG. 21, the right side elevational, front elevational, and back elevational views being identical thereto.

FIG. 23 is a top plan view of the seating of FIG. 21.

FIG. 24 is a bottom plan view of the seating of FIG. 21.

FIG. 25 is a side elevational view rotated approximately 45 degrees from the side elevational view of FIG. 22.

FIG. 26 is an isometric view of a seating showing a sixth embodiment of my new design.

FIG. 27 is a left side elevational view of the seating of FIG. 26.

FIG. 28 is a top plan view of the seating of FIG. 26.

FIG. 29 is a bottom plan view of the seating of FIG. 26.

FIG. 30 is a side elevational view rotated approximately 18 degrees from the side elevational view of FIG. 27.

FIG. 31 is an isometric view of a seating showing a seventh embodiment of my new design.

FIG. 32 is a left side elevational view of the seating of FIG. 31.

FIG. 33 is a top plan view of the seating of FIG. 31.

FIG. 34 is a bottom plan view of the seating of FIG. 31.

FIG. 35 is a side elevational view rotated approximately 18 degrees from the side elevational view of FIG. 32.

FIG. 36 is an isometric view of a seating showing an eighth embodiment of my new design.

FIG. 37 is a left side elevational view of the seating of FIG. 36.

FIG. 38 is a top plan view of the seating of FIG. 36.

FIG. 39 is a bottom plan view of the seating of FIG. 36.

FIG. 40 is a side elevational view rotated approximately 18 degrees from the side elevational view of FIG. 37.

FIG. 41 is an isometric view of a seating showing a ninth embodiment of my new design.

FIG. 42 is a left side elevational view of the seating of FIG. 41.

FIG. 43 is a top plan view of the seating of FIG. 41.

FIG. 44 is a bottom plan view of the seating of FIG. 41; and,

FIG. 45 is a side elevational view rotated approximately 18 degrees from the side elevational view of FIG. 42.

The broken line showing of a table and legs joining the seats to the table in FIGS. 1-45, and the broken line showing of brackets joining the seat back to the seat bottom in FIGS. 1-45 are included for the purpose of illustrating use and environment and form no part of the claimed design.
